UNITED STATES PATENT OFFICE

ARTHUR J. REED, OF PHILADELPHIA, PENNSYLVANIA

DRAFT-REGULATING APPLIANCE FOR FURNACES

Application filed January 30, 1929. Serial No. 336,035.

My invention relates to the draft control of furnaces, more particularly of domestic furnaces, and has for its object to supply a simple, convenient and effective device for 5 directing the air supply to support combustion in furnaces partly into the ash pit and partly into the fire box in properly regulated proportions and my invention consists in a draft directing and regulating appliance 10 and in its combination with a furnace and a fan for supplying air.

The nature of my improvements will be best understood as described in connection with the drawings in which it is illustrated 15 and in which

Figure 1 is a side elevation of a furnace equipped with my improved device, the draft regulating appliance being shown in section; Figure 2 is a cross section on the line 2—2

20 of Fig. 1; Figure 3 is a perspective view of my draft regulating appliance;

Figure 4 an end view thereof;

Figure 5 a similar end view showing a 25 modification of the damper construction; Figure 6 is a sectional elevation on the line 6—6 of Fig. 5 and

Figure 7 is a sectional plan view through the fire box of the furnace showing a modification of the appliance for introducing air 30 into the fire box.

A indicates the furnace; A¹ the grate; A² the ash pit; A³ the fire box; A⁴ and A⁵ indicating doors closing apertures leading into 35 the ash pit and fire box. B is a fan for supplying air to support combustion in the furnace, the air being delivered through a conduit B¹. C is a flexible conduit section by which the conduit B¹ is connected to the end 40 section D¹ of my draft regulating appliance indicated at D.

As shown, the parts D and D¹ are formed of separate castings forming, when united, an air conduit adapted to be inserted in the furnace wall so as to project into the ash pit and having formed between them an opening adapted to receive a damper or dampers. At one side of the conduit D is formed a lateral chamber D², this chamber being 50 formed by means of an internal partition d²

and opening, as shown, in the direction from which the air is flowing through the conduit. The open end of this chamber D² comes practically flush with the opening formed for the reception of the damper or 55 dampers and the chamber opens into a conduit section D³ which is connected by a conduit D⁴ with the fire box of the furnace, as indicated in Figs. 1 and 2. E, Fig. 4, indicates a sliding damper which is laterally 60 movable in the conduit D and a portion of which, preferably chamfered off as shown at E¹, extends over the opening of the chamber D².

In the modification shown in Fig. 5, two 65 dampers are provided, one, indicated at F, being adapted to regulate the draft through the conduit D and the other, indicated at F¹ being adapted to regulate the draft into the chamber D².

In the modification shown in Fig. 7, an 70 air distributor, indicated at D⁶, is located in the fire box and connected with the pipe or conduit D⁴, which, in Fig. 2, is shown as simply having a nozzle D⁵ opening into the 75 fire box.

In operation air supplied by the fan B is delivered into the conduit and regulating device D in which it is divided, a portion passing into the ash pit and a portion passing into the chamber D² and thence through the connections described into the fire box. A proper apportionment of the air supplied at each point is provided for by the adjustment of the dampers. In practice I make the area of the chamber D² of about the proper proportion to the area of the conduit D to effect a proper apportionment of the air delivered into the fire box and the ash pit and in such case a single damper such as indicated at E is used to simultaneously regulate the draft of both the ash pit and the fire box; a necessary regulation however may be effected by utilizing two dampers such as are indicated at F and F¹.

Having now described my invention, what I claim as new and desire to secure by Letters Patent is:

1. In combination with a furnace and a fan for supplying air to the furnace, an air

100

- conduit opening into the ash pit of the furnace having a lateral branch and a chamber formed by an internal partition of the air conduit extending from the top of the air conduit and between the sides thereof in such manner as to form a divisional chamber therein opening in the direction from which the air flows through the conduit and formed to direct a definite portion of the air current into the lateral branch, and damper mechanism located in the conduit for controlling the flow of air through the main and branch conduits said branch conduit leading to the fire box of the furnace.
- 15 2. A draft control appliance for furnaces consisting of an air conduit section adapted to enter the ash pit of a furnace having a lateral outwardly opening chamber formed in it by an internal partition wall of the air conduit extending from the top of the air conduit and between the sides thereof in such manner as to form a divisional chamber therein, a branch air conduit leading from said lateral chamber, and damper mechanism arranged to regulate the air flow through the main conduit and into the lateral chamber thereof.
